United States Patent Office.

J. C. PINNER, OF NEWBERN, TENNESSEE.

Letters Patent No. 96,263, dated October 26, 1869.

IMPROVEMENT IN SCREW-DRIVER.

The Schedule referred to in these Letters Patent and making part of the same.

To all whom it may concern:

Be it known that I, J. C. PINNER, of Newbern, in the county of Dyer, and State of Tennessee, have invented a new and improved Screw-Driver; and I do hereby declare that the following is a full, clear, and exact description of the construction and operation of the same, reference being had to the accompanying drawings making part of this specification, in which—

Figure 1 is a side view.

Figure 2 is a longitudinal vertical section.

The object of this invention is to provide for public use a simple and convenient tool, with which a screw can be more readily and easily inserted or removed than with the other screw-drivers heretofore brought into use.

To this end, my improved screw-driver is made with two spring jaws, which, by means of a sliding ring or strap, can be brought together so as to grasp and hold the screw-head, and answer for the purpose of inserting or removing the screw, so long as the latter works without much friction or resistance. At the same time, if the screw moves with difficulty, and is disposed to slip in the jaws, a blade like that of an ordinary screw-driver can be used, either in combination with or independent of said jaws.

In the drawings—

A is the handle, and B is the shaft or stem of an ordinary screw-driver, terminating in a sharp blade, C.

This blade has two lateral shoulders, c c, at its upper end; and just above them the rod or stem B is provided with a square gain, b, on each side.

A stout metallic ferrule, A', is attached to the handle, provided with radial ribs a a.

D is a stout block, preferably of octahedral shape, having a central bore, and sliding loosely on the stem B.

Its upper end is provided with radial grooves, or notches d d, which fit over the ribs a a, when the block is slid down against the ferrule, and prevent the block from turning independently of the handle and stem, so long as the rib is thus kept in the groove.

To the opposite end of the block two stout curved spring jaws, E E, are firmly fastened, said jaws extending toward the blade C, and curving slightly outward, and then sharply inward, terminating in square faces e e, opposite and parallel to each other, as shown in fig. 2, and having notches v v cut in them, adapted to receive the edges of screw-heads.

A ring, strap, or link, S, oblong in shape, embraces both jaws, just above the end of the block D, and

slides up and down thereon, it being so narrow that it cannot drop down over the block D, and so short that it cannot escape over the outward bend of the jaws E E.

The spring of the jaws is outward, and the function of the sliding clasp or strap is to force them together, so that they will take against the sides of the bit or stem in the gain b, and hold it firmly, or, when they are slid outward far enough, to bring them together against the head of the screw, causing its edges to sink into the depressions v v.

The operation of this improved instrument is easy, simple, and convenient. The block and jaws can be slid up out of the way, so as to let the blade C operate as an ordinary screw-driver.

At the same time, if great force is to be exerted in order to turn the screw, the jaws can be brought together against the stem, at the gains b b, and fastened in that position, when they will operate as braces, imparting to it great additional strength.

If the screw is to be used in wood, or elsewhere where it will work easily, the jaws may be run out beyond the end of the blade C, then brought together and clamped against the head of the screw, as above described, whereby they will hold it securely until it is inserted so far as to maintain its position, or until removed altogether from the wood or other material.

If the screw has a tendency to turn when held by the jaws alone, the blade C may be thrust down against it, and made to enter the notch in the head of the screw, and thereby hold it steady. The blade cannot turn under such circumstances, for the reason that the jaws on either side will prevent it.

I wish it to be understood that I do not claim any of the parts herein described separately considered; but

Having thus described my invention,

What I claim as new, and desire to secure by Letters Patent, is—

The instrument above described, consisting of the handle A, ferrule A', having rib a; block D, having notch d; stem B, having gains b b; blade C, having shoulders c c; spring jaws E E, shaped as described, and having grooves v v, and sliding clasp or strap S, all constructed substantially in the manner and for the purposes herein set forth.

J. C. PINNER.
